UNITED STATES PATENT OFFICE.

FREDERICK H. MEUNIER, OF DENVER, COLORADO.

GOVERNOR FOR PLAYER-PIANOS.

1,321,117.

Specification of Letters Patent. Patented Nov. 11, 1919.

Application filed June 27, 1917. Serial No. 177,273.

To all whom it may concern:

Be it known that I, FREDERICK H. MEUNIER, a citizen of the United States, residing at Denver, in the county of Denver and State of Colorado, have invented certain new and useful Improvements in Governors for Player-Pianos, of which the following is a specification.

My invention relates to improvements in governors of the type used on player pianos to automatically regulate the velocity of an air-current through the motor with which it is associated, and thereby insure a uniform movement of the same irrespective of the pressure applied to the pedals which by their action upon a suitable pumping appliance, produces the flow of air by which the motor is operated.

In governors at present in use, the air current drawn through the motor by the partial vacuum produced by the pumping action of the pedals, passes through an opening partially covered by the tempo-valve and thence through a port the opening of which is automatically regulated by means of a pressure-controlled valve, in accordance with the degree of vacuum produced by the pedal action.

If the pressure upon the pedals is increased beyond the normal, the pressure-controlled valve closes its port in accordance with the proportionately increased suction and the air-current is thus sufficiently retarded to prevent the excess suction from accelerating the velocity of the motor beyond that predetermined by adjustment of the tempo-valve.

When the pressure upon the pedals is decreased and the governor valve is in consequence moved to increase the opening of its port and thereby permit of the passage of a larger volume of air to prevent slowing of the motor to a less than normal velocity, the tempo-opening through which the current must pass to reach the automatically controlled port and which remains the same under all conditions, has a retarding influence upon the air flow and thereby diminishes the velocity with which it is drawn through the motor.

As a result of this condition the desired uniform action of the motor is not obtained when the pedal action is decreased and it is the object of the present invention to correct this faulty operation of the governor by providing a by-pass around the tempo-opening,

the flow through which is controlled by a movement of the same pressure controlled medium which operates the governor valve, to increase the volume of air moving from the motor past the tempo-valve to the automatically regulated port of the governor, in accordance with the decrease in vacuum by a diminished movement of the pumper pedals.

An illustrative embodiment of my invention is shown in the accompanying drawings in the various views of which like reference characters designate corresponding parts of the mechanism and in which—

Figure 1 represents a plan view of a governor to which my invention is applied with its cover board removed and the ported support of the automatic valves shown in horizontal section.

Fig. 2, a vertical section taken along the line 2—2, Fig. 1.

Fig. 3, a similar section along the line 3—3, Fig. 1.

Fig. 4, a horizontal section taken on a plane indicated by the lines 4—4, in Fig. 3.

Fig. 5, a transverse section along the line 5—5, Fig. 1.

Fig. 6, a section taken along the line 6—6, Fig. 1, and

Fig. 7, a section along the line 7—7, Fig. 1.

Referring more specifically to the drawings the reference numeral 2 designates the box of the governor, which by means of vertical and horizontal partitions is divided into a number of chambers or compartments which are interconnected by openings in the partitions to provide an indirect passage between an air admission opening 3 in an end of the box which connects with the motor, and an air-egress or suction opening 4 in the opposite end of the same which connects with the bellows or other pumping device operated by the pedals of the player-piano.

The compartments into which the box is divided, considered in the order of their successive arrangement for the passage of the air-current through the governor, are the compartment 5 in the upper half of the box which connects with the opening 3 and which has in its bottom a tapering tempo-opening 6, the compartment 7 in the lower half of the box directly below the first-mentioned compartment, the compartment 8 in the upper half of the box connected with the last-mentioned compartment by the openings 9 and 10 and containing the valve-support 12. This valve-support has in one of

its sides a port 13 in connection with an opening 14 in the bottom of the compartment 8 to connect said compartment with a compartment 15 in the lower half of the box 5 which is in direct communication with the before-mentioned suction-opening 4 connecting with the pumping device.

The normal direction of the air current between the openings 3 and 4 has been indicated in the drawings by arrows designated successively by the letters A, B, C, D, E, F, G, H and I.

The passage of the air-current through the port 13 is controlled by a valve 16 pivoted 15 on the support as at 17 and connected with a bellows 18 which covers the compartment 8.

The valve is held against its seat by a spring 19 and its connection with the bellows is established through the medium of a bracket 20 depending from the top-board 20 of the same.

A spring 21 applied between a rearwardly extending arm 22 on the bellows and an extension 23 on the bottom of the box tends to 25 maintain the bellows in a wide-open position against the suction produced by the partial vacuum maintained in the compartment 8 by the pedal action of the instrument.

The tempo-valve 24 consists of a slide 30 which is held in engagement with the bottom surface of the compartment 5 by a spring 25 and which is connected with a rod 26 extending through an opening in an end of the box 2 to adjust its position with relation to the 35 tempo-opening which in the operation of the instrument is partially covered thereby.

The compartment 15 which connects with the port 13 controlled by the valve 16, is also connected by an opening 27 with a compartment 40 28 divided from the compartment 7 in the lower part of the box and connected with the valve-compartment 5 by an opening 29.

The flow through this opening is controlled 45 by a slide-valve 30 held in engagement with the bottom surface of the compartment 5 by a spring 31 and connected with a rod 32 which extends through an opening in the end of the box for its adjustment.

The purpose of the valve 30 is to effect a direct connection between the admission opening 3 and the suction-opening 4 of the governor when it is desired to accelerate the 55 velocity of the motor when the music sheet of the player-piano is rewound upon its spool, and the valve has no relation to the parts of the governor to which the improvements included in my invention are applied.

60 The improvements which constitute my invention consist first of all in providing adjacent the tempo-opening, one or more auxiliary openings 33; subdividing the compartment 7 with which these openings connect, by a transverse partition 34 to provide

a compartment 35, subdividing the compartment 15 which connects with the valve-controlled port 13, by a partition 36 to provide a compartment 37 which is connected with the compartment 35 by an opening 38; 70 providing the valve-support 12 with a second port 39 which connects with an opening 40 in the bottom of the compartment 8 to establish a communication between said compartment and the compartment 37; and 75 providing a valve 41 to automatically control the port 39 by connection with the bellows 18.

The valve 41 which is pivoted as at 42 at the side of the support 12 opposite to that 80 at which the valve 16 is positioned, is held in engagement with its seat by a spring 43.

The valve is connected with the bellows by a threaded rod 44 which extends through a hole in the top-board of the bellows, and 85 a nut 45 which is screwed onto the rod in engagement with a lug 46 extending over the hole through which it projects.

The area of the port 39 controlled by the valve 41 is automatically regulated proportionate to that of the opening 6 uncovered by the tempo-valve 24, by means of a slide 47 disposed between the valve 41 and the port 39 to partially cover the latter.

The slide is attached at an end of a rod 48 which extends through an opening in the 95 end of the box 2.

The tempo-valve 24 and the slide 47 are connected for synchronous movement to simultaneously cover or uncover the respective openings at a predetermined ratio, by a lever 49 which is fulcrumed as at 50 upon a bracket 51 fastened exteriorly of the box, and pivotally connected with the two rods 48 and 26 as at 52 and 53.

In the operation of a governor constructed in accordance with my invention, the tempo-valve is moved to regulate the size of the opening it controls in accordance with the requirements of the musical composition it is desired to execute on the piano.

The area of the port 39 is by the synchronous movement of the slide-valve 47 regulated in predetermined ratio to the uncovered portion of the tempo-opening, to prevent a flow of air through the port in excess of the volume permitted to pass through said opening.

After this adjustment, the governor is in the proper condition to automatically regulate the volume of the air-current passing through the motor by the partial vacuum produced by the pedal action and thereby insure a uniform movement of the motor irrespective of variations in the pressure on the pedals.

When the pressure upon the pedals is increased, the proportionately increased vacuum causes the bellows to collapse against the action of the spring 21, thereby closing 13

the valve 16 and reducing the opening of the port 13.

The velocity of the air-current produced by the action of the pedal operated suction-appliance to effect the operation of the motor, thus remains the same irrespective of the increased suction.

When the pressure upon the pedals is diminished and the suction is in consequence reduced, the bellows are extended by the contraction of the spring 21 and opens the valve 16 which controls the air-flow through the port 13.

The increased opening of the port 13 would cause an increase in the volume of air passing from the motor through the governor, were it not for the fact that the size of the tempo-opening remains the same and restricts the free passage of the increased volume of motive fluid.

In the governor containing the improvements constituting my invention as hereinbefore described, this defect is effectively remedied by the opening movement of the auxiliary valve 41 which also is connected with the bellows.

The valve which normally covers the port 39 and thereby closes the by-pass for the air-current auxiliary to the tempo-opening, uncovers said port when moved to its open position by the extension of the bellows caused by a diminished pressure upon the pedals of the instrument as hereinbefore explained and thereby permits the passage of an air-current between the openings 3 and 4 auxiliary to that passing through the tempo-openings along a path which commencing with the compartment 5 includes in successive order, the auxiliary tempo-openings 33, the compartment 35, the opening 38, the compartment 37, the opening 40 in the bottom of the valve-support, the opening 39 controlled by the valve 41, the compartment 8, the opening 13 of the valve-box controlled by the valve 16 which was moved to its open position by the extension of the bellows, the port 14 in the bottom of the valve-support 12, the compartment 15 and the opening 16 which connects with the suction-opening 4.

The direction of the air-currents through the by-pass auxiliary to the tempo-opening as herein described has been indicated in the drawings by arrows designated successively by the letters *a, b, c, d, e, f, g, h* and *i*.

It will be readily seen that the area of the port 39 uncovered by the valve 41, is regulated in accordance with the decrease of the air-pressure in the chamber 8 and that in consequence the outlet of the passage which supplements that restricted by the tempo-opening, is correspondingly increased or reduced in area.

It will thus be understood that by the use of my improved governor, the velocity of

the air-current passing through the motor remains substantially uniform during a decrease in suction produced by the pedal-action as well as during an increase thereof and that in this respect it produces an effect 70 which for the reasons mentioned hereinbefore, is not obtained in the operation of a governor of ordinary construction.

Having thus described my invention what I claim and desire to secure by Letters-75 Patent is:

1. In a governor for player pianos, the combination of a casing having an admission-opening and a suction-opening and a passage between them, an adjustable tempo-valve and a valve operated by air-pressure variations, controlling the flow of air through successive parts of the passage, a by-pass auxiliary to the part of the passage controlled by the tempo-valve, and a valve 85 cooperative with the first-mentioned valve to open said by-pass proportionate to a decrease in a vacuum produced at the suction-opening.

2. In a governor for player-pianos, the combination of a casing having an admission-opening and a suction-opening and a passage between them, an adjustable tempo-valve and a valve operated by air-pressure variations, controlling the flow of air 95 through successive parts of the passage, a by-pass auxiliary to the part of the passage controlled by the tempo-valve, and a valve operated by a decrease in a vacuum produced at the suction-opening, to open said by-pass.

3. In a governor for player-pianos, the combination of a casing having an admission-opening and a suction-opening and a passage between them, an adjustable tempo-valve to restrict the flow of air through a 105 part of said passage, a bellows operated by variations in air-pressure in said passage, a valve connected with said bellows to automatically restrict the flow of air through another part of the passage, and a valve co-operative with said automatic valve to increase the carrying capacity of the part of the passage controlled by the tempo-valve, proportionate to decrease in a vacuum produced at the suction-opening.

4. In a governor for player-pianos, the combination of a casing having an admission-opening and a suction-opening and a passage between them, an adjustable tempo-valve to restrict the flow of air through a 120 part of said passage, a bellows operated by variations in air-pressure in said passage, a valve adapted to automatically restrict the flow of air through an other part of the passage, and a valve connected with said bellows to increase the conductive capacity of the part of the passage controlled by said tempo-valve, proportionate to a decrease in a vacuum produced at the suction-opening.

5. In a governor for player-pianos, the

- combination of a casing having an admission-opening and a suction-opening and a passage between them, an adjustable tempo-valve and a valve operated by air-pressure variations controlling the flow of air through successive parts of the passage, a by-pass auxiliary to the part of the passage controlled by the tempo-valve, a valve co-operative with the tempo-valve to restrict the flow of air through the by-pass, and a valve co-operative with the first-mentioned valve to open said by-pass proportionate to a decrease in a vacuum produced at the suction-opening.
6. In a governor for player-pianos, the combination of a casing having an admission-opening and a suction-opening and a passage between them, an adjustable tempo-valve and a valve operated by air-pressure variations, controlling the flow of air through successive parts of the passage, a by-pass auxiliary to the part of the passage controlled by the tempo-valve, an adjustable valve to restrict the flow of air through the by-pass, and a valve adapted to automatically open said by-pass proportionate to a decrease in a vacuum produced at the suction-opening.
7. In a governor for player-pianos, the combination of a casing having an admission-opening and a suction-opening and a passage between them, an adjustable tempo-valve controlling the flow of air through a part of said passage, a by-pass auxiliary to said part of the passage, and a valve operated by air-pressure variations, to open said by-pass proportionate to a decrease in a vacuum produced at the suction-opening.
8. A governor for player pianos comprising in combination, a box having a suction-opening and an admission-opening, and divided into communicating compartments which form a passage connecting said openings, one of said compartments having primary and auxiliary tempo-openings and another compartment having ports respectively connecting the tempo-openings with the suction-opening, a valve operated by air-pressure variations, a valve connected with the bellows to automatically open and close the port communicating with the primary tempo-opening, a valve co-operative with the first valve to open the other port proportionate to a decrease in a vacuum produced at the suction-opening, and an adjustable tempo-valve controlling the flow of air through the primary tempo-opening.
9. A governor for player-pianos comprising in combination, a box having a suction-opening and an admission-opening, and divided into communicating compartments which form a passage connecting said openings, one of said compartments having primary and auxiliary tempo-openings, and another compartment having ports respec-
- tively connecting the tempo-openings with the suction-opening, a valve operated by air-pressure variations to open and close the port communicating with the primary tempo-opening, an adjustable tempo-valve controlling the flow of air through the primary tempo-opening, a valve co-operative with the first-mentioned valve to open the last-mentioned port proportionate to a decrease in a vacuum produced at the suction-opening.
10. A governor for player-pianos comprising in combination, a box having a suction-opening and an admission-opening, and divided into communicating compartments which form a passage connecting said openings, one of said compartments having primary and auxiliary tempo-openings and another compartment having ports respectively connecting the tempo-openings with the suction-opening, a valve operated by air-pressure variations to open and close the port communicating with the auxiliary tempo-opening, and a valve co-operative with the first-mentioned valve to open the last-mentioned port proportionate to a decrease in a vacuum produced at the suction-opening.
11. A governor for player pianos comprising in combination, a box having a suction-opening and an admission opening, and divided into communicating compartments which form a passage connecting said openings, one of said compartments having primary and auxiliary tempo-openings, and another compartment having ports respectively connecting the tempo-openings with the suction-opening, a valve operated by air-pressure variations to open and close the port communicating with the primary tempo-opening, an adjustable tempo-valve controlling the flow of air through the primary tempo-opening, a valve co-operative with the tempo-valve to regulate the effective area of the port communicating with the auxiliary tempo-opening, and a valve co-operative with the first-mentioned valve to open the last-mentioned port, proportionate to a decrease in a vacuum produced at the suction-opening.
12. A governor for player pianos comprising in combination a box having a suction-opening and an admission-opening, and divided into communicating compartments which form a passage connecting said openings, one of said compartments having primary and auxiliary tempo-openings and another compartment having ports respectively connecting the tempo openings with the suction-opening, a bellows operated by air-pressure variations, a valve connected with the bellows to automatically open and close

the port communicating with the primary tempo-opening, an adjustable tempo-valve controlling the flow of air through the primary tempo-opening, an adjustable valve 5 to regulate the effective area of the port communicating with the auxiliary tempo-opening, and a valve coöperative with the first-mentioned valve to open the last-men-

tioned port proportionate to a decrease in a vacuum produced at the suction-opening. 10

In testimony whereof I have affixed my signature in presence of two witnesses.
